UNITED STATES PATENT OFFICE.

RICHARD SMITH, OF DENVER, AND PETER CHRISTENSEN, OF FORT LOGAN, COLORADO.

CAR-TRUCK.

No. 901,396.

Specification of Letters Patent.

Patented Oct. 20, 1908.

Application filed August 12, 1907. Serial No. 388,274.

To all whom it may concern:

Be it known that we, RICHARD SMITH and PETER CHRISTENSEN, citizens of the United States of America, residing, respectively, at 5 Denver, in the county of Denver and State of Colorado, and at Fort Logan, in the county of Arapahoe and State of Colorado, have invented certain new and useful Improvements in Car-Trucks, of which the following is a specification.

This invention relates to car trucks, and more especially to certain new and useful improvements in the so-called center-bearing trucks, which are designed to move laterally 15 and around their centers, independent of the car supported thereon.

The objects of our invention are, to provide a truck of the class named, in which simplicity of construction is combined with 20 strength and durability, which, by its peculiar construction, promotes the stability of the car body and renders its motion even and equable, and in which the position of the moving parts may be readily adjusted by the 25 application of detachable wearing plates. We attain these objects by the mechanism illustrated in the accompanying drawings in the various views of which, like parts are similarly designated and in which

30 Figure 1 represents a plan view of the truck; Fig. 2, a side elevation thereof; Fig. 3 a transverse section taken along a line 3-3, Fig. 1. Fig. 4, an enlarged section along a line 4-4, Fig. 3. Fig. 5, an enlarged section along a line 5-5, Fig. 1. Fig. 6, a section taken along line 6-6, Fig. 5. Fig. 7, a section taken along a line 7-7, Fig. 1. Fig. 8, a section taken along a line 8-8, Fig. 7. Fig. 9, a sectional view of the center- 40 plates on the truck bolster and the car body, in their relative positions, and Fig. 10, a top view of the center-plate on the truck bolster.

Referring to the drawings, let the reference numeral 10 designate the rectangular 45 truck frame, including the side beams 10^a, and the therefrom depending pedestal jaws 11, in between which are arranged the journal boxes 12, which support the extremities of the axles 13 on the wheels 14.

50 Wearing plates 15, placed between the sides of the boxes 12 and the jaws, are composed of channel iron, the flanges 16 of which engage the inner and outer surfaces of the jaws and protect them against wear

by contact with adjacent movable parts of 55 the truck. The plates 15 being held in place without the use of bolts or other fastening means, may be readily removed and interchanged with others, in case of wear or breakage.

60 The truck frame 10, rests upon eight coiled springs 17 and 18, arranged underneath the side beams 10^a and supported upon the equalizers 19, which are suspended from the axle boxes on the outside of the wheels 14. Each 65 equalizer comprises two parallel bars 20 disposed on opposite sides of the pedestals, and which being secured in spaced relation to each other by means of a plurality of distance bolts 21, support the transversely disposed 70 seats 22, which bear the above named springs. Two of the four springs arranged below each of the side beams 10^a, designated in the drawings by the numeral 17, are disposed intermediate the two axle boxes, while 75 the outer, shorter ones 18, rest upon extensions 19^a of the equalizers 19, beyond the pedestal jaws and in proximity to the ends of the truck frame. The springs thus arranged, assure an even movement of the 80 truck frame in relation to the two equalizers, and effectually prevent rocking of the car-body, which is supported thereupon through instrumentality of the truck bolster 23. The latter consists of two connected beams 24, 85 preferably composed of channel iron and disposed between and in parallel relation to two beams 25, made of angle iron, which being arranged at equal distances from the transverse axis of the frame, connect the 90 parallel side beams 10^a, below which the equalizers extend.

Four wearing plates 26, provided with offset, outwardly ranging flanges 26^a, are secured upon the vertical sides of the bolster, 95 by means of bolts 27 inserted in registering apertures in the said sides and the therewith contiguous flanges, and engage the opposite, inner surfaces of the parallel beams 28, for the purpose of preventing lateral displacement of the bolster during its longitudinal, reciprocating movement. The plates 26 being thus detachably secured, are readily accessible, and may be removed or renewed, 100 in case of wear or breakage.

105 The truck bolster 23 is secured at its ends, upon two sets of elliptic springs 28, which are fastened upon the subjacent extremities

of the so-called sand-board 29. The latter, being composed of channel iron, combines strength with lightness, and being bent in the form of an arc, it provides an unobstructed space for the brake-rods and other appliances disposed below the body of the car. The member 29 extending underneath and in parallel relation to the truck bolster, is movably supported at its extreme ends 10 upon the transverse portions 30^a of two U shaped hangers or stirrups 30, the upwardly ranging, normally vertical arms 30^b of which, extend between the sides of the bolster and the parallel, transverse beams 25, and are 15 pivotally suspended from the latter by means of pins 31, projecting through corresponding apertures in their extremities and supported in boxes 32 which are secured upon the upper surface of the stationary beams.

20 The movable connection between the extremities of the sand-board and the subjacent transverse portions of the hangers 30, is established by means of ridged dies 33 secured upon the said portions 30^a, and which 25 extend in correspondingly formed grooves 34 in blocks 35, which are fixed against the lower surface of the extremities of the member 29 and intermediate the depending flanges of the angle iron of which it is 30 composed.

As the ends of the bolster are spaced from the inner surfaces of the side beams 10^a of the truck frame, the former is free to move laterally in constant parallel relation to the 35 upper surface of the latter, by the oscillatory motion of the hangers 30, and the consequent rocking movement of the dies 33, within the recesses 34 when, on rounding curves or by reason of imperfections in the railroad track, 40 the trucks are forced to laterally deviate from its course of travel.

The car body 36 is pivotally supported upon the truck bolster by means of a pin 37 which passes through vertically aligned 45 apertures 38 and 38^a in the center plates 39 and 40, respectively secured upon the bolster in central relation thereto and against the floor structure of the car body. .

The center plate 39 has a runway 39^a, concentric with the aperture 38^a which in practice is occupied by a correspondingly formed depending ridge on the superposed plate 40, and is furthermore provided with an internal, annular channel 39^c concentric with 50 the said runway and connecting with the upper surface of the plate by means of a plurality of vertical passages 39^d.

The channel is, in practice, filled with a 55 suitable lubricant, such as oil, which is conducted in between the contacting surfaces of the two plates 39 and 40, by wads of cotton waste or other absorbent material, with which the passages 39^d are filled, and which 60 extend into the channel, as indicated in the 65 drawings.

As the operation of the various parts comprised in our improved truck, and the advantages derived therefrom, have been referred to at intervals in the course of the description, it will not be necessary to go 70 into further explanation at this point, and

Having described our invention, what we claim and desire to secure by Letters Patent, is

1. In a center bearing truck, in combination a truck frame, journal boxes having a vertical movement thereon, equalizers suspended from the said boxes and having longitudinal extensions projecting beyond the same, a truck bolster associated with the 80 said frame to have an oscillatory movement transversely in relation thereto, independent of the equalizers, springs seated upon the latter in engagement with the frame in between the said boxes and springs seated 85 upon the said extensions in engagement with the frame in proximity to its extremities.

2. In a center bearing truck, in combination a truck frame including transverse parallel beams, journal boxes having a vertical 90 movement on the frame, equalizers suspended from the said boxes and having longitudinal extensions projecting beyond the same, springs seated upon the equalizers in engagement with the frame in between the 95 said boxes, springs seated upon the said extensions in engagement with the frame in proximity to its extremities, oscillatory hangers suspended from the said beams, a sand board hingedly supported within the said 100 hangers and a truck bolster supported upon the said board.

3. In a center bearing truck, in combination a truck frame including transverse parallel beams, journal boxes having a vertical 105 movement on the frame, equalizers suspended from the said boxes and having longitudinal extensions projecting beyond the same, springs seated upon the equalizers in engagement with the frame in between the 110 said boxes, springs seated upon the said extensions in engagement with the frame in proximity to its extremities, oscillatory hangers suspended from the said beams, a sand board hingedly supported within the said 115 hangers, springs upon the said board and a truck bolster supported upon the said springs.

4. In a center bearing truck, the combination with the truck frame having transverse, parallel beams, of a truck bolster movably supported between the latter and a center plate comprising two superposed members, the lower one of which has an internal annular chamber and a plurality of passages 120 connecting the said chamber with the upper surface of the said member and containing absorbent material engaging the lower surface of the upper member.

5. In a center-bearing truck, the combina- 130

tion with the truck-frame having transverse parallel beams, of oscillatory hangers suspended from the latter, a sand-board movably supported within the said hangers and
5 comprising a channeled plate bent in the form of an arch, and a truck - bolster supported upon the said board.

In testimony whereof we have affixed our signatures in presence of two witnesses.

RICHARD SMITH.
